(57) **CLAIM**

The ornamental design for a cycle lock, as shown and described.

DESCRIPTION

FIG. 1 is a perspective view of a cycle lock according to a first preferred embodiment of my new design;

FIG. 2 is a top plan view of the cycle lock of FIG. 1;
FIG. 3 is a bottom plan elevational view of the cycle lock of FIG. 1;

FIG. 4 is a front elevational view of the cycle lock of FIG. 1;

FIG. 5 is a rear elevational view of the cycle lock of FIG. 1;
FIG. 6 is a left side elevational view of the cycle lock of FIG. 1;

FIG. 7 is a right side elevational view of the cycle lock of FIG. 1;

FIG. 8 is a perspective view of a cycle lock according to a second preferred embodiment of my new design;

FIG. 9 is a top plan view of the cycle lock of FIG. 8;
FIG. 10 is a bottom plan elevational view of the cycle lock of FIG. 8;

FIG. 11 is a front elevational view of the cycle lock of FIG. 8;

FIG. 12 is a rear elevational view of the cycle lock of FIG. 8;

FIG. 13 is a left side elevational view of the cycle lock of FIG. 8; and,

FIG. 14 is a right side elevational view of the cycle lock of FIG. 8.

The dashed lines in FIGS. 1-14 represent environment and are for illustrative purposes only and do not constitute part of the claimed design. The phantom lines in FIGS. 1-14 define the border between claimed and unclaimed matter.
